US00D503937S

(12) **United States Design Patent** (10) Patent No.: **US D503,937 S**
Tani (45) Date of Patent: **** Apr. 12, 2005**

(54) **MULTI-FUNCTION FACSIMILE MACHINE**

(75) Inventor: **Atsushi Tani**, Fukuoka (JP)

(73) Assignee: **Matsushita Electric Industrial Co., Ltd.**, Osaka (JP)

(**) Term: **14 Years**

(21) Appl. No.: **29/198,876**

(22) Filed: **Feb. 5, 2004**

(30) **Foreign Application Priority Data**

Dec. 12, 2003 (JP) 2003-036911

(51) LOC (7) Cl. **16-03**

(52) U.S. Cl. **D14/462**

(58) Field of Search D14/462-465;
D18/36, 367; 358/400, 401, 501-506

(57) **CLAIM**

The ornamental design for a multi-function facsimile machine, as shown and described.

DESCRIPTION

FIG. 1 is a top perspective view of a multi-function facsimile machine of the present invention;

FIG. 2 is a front view thereof;

FIG. 3 is a first side view thereof;

FIG. 4 is a second side view thereof;

FIG. 5 is a top view thereof;

FIG. 6 is a bottom view thereof; and,

FIG. 7 is a rear view thereof.

1 Claim, 5 Drawing Sheets
